UNITED STATES PATENT OFFICE.

SHREWSBURY B. MILLER, OF FAIRMONT, WEST VIRGINIA.

JOINTER FOR CONCRETE ROADS.

Application filed January 20, 1922. Serial No. 530,730.

To all whom it may concern:

Be it known that I, SHREWSBURY B. MILLER, a citizen of the United States, residing at Fairmont, in the county of Marion 5 and State of West Virginia, have invented a new and useful Jointer for Concrete Roads, of which the following is a specification.

My invention relates to improvements in forming a joint or line of weakness in a concrete slab, such as a concrete road, along 10 which line the concrete will crack or separate, sometime after the slab has hardened and become set, when stressed by shrinkage strains. It has been my observation and belief 15 come my belief that concrete roads shrink more than expand, and that contraction always takes place first, therefore, I provide a contraction crack that will subsequently allow for expansion, and that no expansion joint with asphaltic filler is necessary.

By using my method for dividing a length of concrete road into any desired number of sections to take care of the contraction, in the future, the use of other joints in the concrete is made unnecessary, with a consequent saving in time and expense in laying the concrete. I attain my object by imbedding in the concrete a transverse line of pins or plugs that may be of wood, for example, 25 these pins may have any diameter and of a length to suit the depth of the concrete and as the pins are introduced while the concrete is green or un-set the operation is simple.

It is obvious that this line of pins will weaken the strength of the concrete along this line, because the section of the concrete on this line is less than along some other line where the concrete is of full section. And 30 that when shrinkage stresses appear in the concrete the stresses will be relieved by the concrete separating or cracking along this predetermined line, which line will be straight and the crack vertical, because the pins will be set vertically.

To attain the objects of my invention I use the appliances and attributes illustrated in the accompanying drawings:

Fig. 1 is a plan view of a bar having a 50 length to correspond with the width of the concrete road being constructed, the bar in all views in the drawing being designated (1) along the length of the bar are set the guides (2) at such intervals as may be desired, with handles (3) for lifting and placing the bar.

Fig. 2 shows the bar in side view with guides (2) and handles (3).

Fig. 3 is a plan view of a slab of concrete showing the pins (4) located transversely 60 across the slab, and along which line of pins it is intended the concrete shall open when contraction stresses are set up in the slab.

Fig. 4 is a section of the bar (1) on a plane through a guide (2) showing the pin (4) with pointed end (8) about to be introduced into the guide (2) also the guide (2) extends above the bar a distance (6) and below the bar a distance (5) the lower surface (7) of the bar rests in the concrete surface of the slab.

Fig. 5 shows the "follower" (8) with handle (9) for the purpose of setting the pins the distance (5) below the concrete surface.

Fig. 6 shows a transverse section of a concrete road into which the pins (4) have been set, in the vertical plane in which it is intended the slab shall crack when contraction in the slab takes place.

The operation of my jointer is as follows:

After the concrete road surface has been "struck" to the required contour, the jointer is placed in position near the end of the concrete being placed, and where the section of concrete is full and where bar can be reached to insert the pins without disturbing the placed concrete. Then the required number of pins (4) are placed in the guide (2) and driven into the green concrete to the top of 80 the guide (2). The pin "set" is then used and the pin driven into the concrete as far as the "follower" of the "set" allows. This completes the operation and the surface of the concrete is ready to be "belted" smooth. 95 It is to be noted that the top of the pins are below the surface of the finished concrete and when belted over form a concealed joint.

I claim:

In a concrete slab a plurality of pins or 100 plugs of various cross section placed in the green concrete to induce the concrete to crack or separate along the line of the pins or plugs, when contraction strains occur in the concrete after hardening.

In testimony whereof I hereunto affix my signature in the presence of two witnesses.

SHREWSBURY B. MILLER.

Witnesses:
